COMMUNICATION CLOCK

William Naecker, Suitland, Md., and Carron Giles,
Washington, D. C.

Application May 26, 1938, Serial No. 209,052

4 Claims. (Cl. 58—125)

(Granted under the act of March 3, 1883, as
amended April 30, 1928; 370 O. G. 757)

This invention relates to a communication clock and has for an object to provide a clock wherein the time indicating mechanism consists of a plurality of axially aligned disks or drums 5 with the time indications placed on the edges of the disks or drums in position to be visible through a window. These drums have numerals thereon and are arranged to indicate time to the current minute and are adapted to be 10 rotated by a substantially frictionless drive from any suitable clock operating mechanism.

In communication work, it is always necessary to include the time of sending in the message being sent or the time of receipt on the message 15 being received. The time will necessarily be mentioned by numerals as for instance 10:57 or 23:39 (on a twenty-four hour basis). With a dial clock, errors may arise from the necessity of the operator's reading the dial and interpreting such reading into numerals. With a drum type of clock, the time is indicated in numerals on the edges of the drums and the current time is indicated by the numerals visible through a narrow window through a wall behind which all 25 the other numerals are concealed from view, thereby providing both accurate and easy reading of the time.

A further object of this invention is to provide a drum type of clock, preferably of the 30 twenty-four hour type.

A further object of this invention is to provide a drum type clock in which the drums are rotated periodically with a rapid snap action.

A further object of this invention is to provide 35 a drum type of clock whose drums may be rotated in proper timekeeping sequence by a substantially frictionless drive powered by the power mechanism of any well-known dial type of clock, the drive of the drum clock being connected to the main shaft of the dial clock in such a way and utilizing so little power that the accuracy thereof is not affected.

A further object of this invention is to provide 45 a twenty-four hour drum type clock which may be connected to and powered by the power mechanism of an existing conventional type of clock.

With the foregoing and other objects in view this invention comprises constructions, combinations, and arrangements of parts hereinafter set forth, disclosed, and claimed. In the drawings:

Fig. 1 is a partly elevational, partly fragmentary, and partly sectional view of the drum 55 clock of this invention.

Fig. 2 is a sectional view on line 2—2 of Fig. 1. Fig. 3 is a fragmentary elevational view looking at the right or front face of the minute unit indicating drum.

Fig. 4 is a sectional view on line 4—4 of Fig. 1 looking at the left or back face of the minute unit indicating drum.

Fig. 5 is a sectional view on line 5—5 of Fig. 1 looking at the right or front face of the hour 10 indicating drum and

Fig. 6 is a sectional view through the hour drum showing the drum actuating mechanism on line 6—6 of Fig. 5.

There is shown at 10 a housing provided with 15 a conventional clock dial 11 at the front end thereof of which the hour hand 12 and minute hand 13 behind the glass window 14 are actuated by the usual clock mechanism which may include a power spring casing 15 and gear 16, geared with the usual clock mechanism to the main shaft 17, the clock mechanism being supported in the customary manner between a front plate 18 and a rear plate 19. The power shaft 17 is extended through the rear plate 19 and has fixed thereon a gear 20 meshing with 20 a pinion 21 of a large gear 22. This gear 22 in turn meshes with a pinion 23 which is journaled on the fixed drum shaft 24, one end of which is supported in the plate 19 and the other end of 25 which is fixed in the plate 25 located adjacent the back end of the housing 10. A beveled side wall 26 is provided with a window 27 through which can be read the time indicating numerals 30 consisting of the hour indicating numeral 28 on drum 31, the minute tens indicating numeral 29 on drum 32 and the minute unit indicating numeral 30 on drum 33. Each of these drums 31, 32 and 33 are journaled on the fixed drum shaft 24. As will be observed from Fig. 2, the 35 fixed drum shaft 24 and the drums are offset from the dial clock power shaft 17 and clock face 11, the relative positions being such as shown by the broken line in 11. There are two series of indicating numerals 30 on the minute unit indicating drum 33, each series reading from 0 to 9 and equally spaced thereabout. It is therefore necessary that this drum make three revolutions per hour and the gear ratio of the gear train 20, 21, 22, and 23 is therefore such 40 that the gear 23 rotates three times as fast as the power shaft 17 which operates the hour hand 12. There are four series of numerals 29, each series from 0 to 5 spaced equally thereabout on the minute tens drum 32. There is one series 45

of numerals 28 on the hour drum 31, each series reading from 1 to 12 and spaced equally thereabout. It is therefore necessary that this drum make one revolution per hour and the gear ratio of the gear train 20, 21, 22, and 23 is therefore such 50 that the gear 23 rotates one-third as fast as the power shaft 17 which operates the hour hand 12. There are four series of numerals 29, each series from 0 to 5 spaced equally thereabout on the minute tens drum 32. There is one series 55

of numerals 28 from 00 to 23 inclusive spaced equally thereabout on the hour drum 31.

It is desirable that the window 27 show the time at the beginning of each minute and that the drums be rotated intermittently at the end of each minute with a rapid snap motion and not continuously. For this purpose it is necessary that the continuous rotation of the gear 23, which itself rotates three times an hour, be transmitted into intermittent or step by step rotation of the minute unit indicating drum 33, to thus provide sixty steps or sixty minutes per hour or three complete revolutions per hour, each revolution consisting of twenty individual steps. Fixed to the continuously rotating gear 23 is an arm 34 to whose counterbalancing base 35 is secured a pair of spring fingers 3 and 37 extending alongside and in the same plane of rotation as the arm 34. A light weight drum control disk 38 preferably made of aluminum is journaled on the fixed drum shaft 24 next to the arm 34 and gear 23 and includes a forwardly extending hub 40 carrying a pair of spaced apart forwardly projecting pins 41 and 42.

The edge of the drum control disk 38 is provided with twenty equally spaced notches 39 and the pins 41 and 42 are spaced apart a distance about equal to the spacing between the center of the notches 39. The arm 34 and spring fingers 36 and 37 extend between the pins 41 and 42. As already apparent arm 34 rotates continuously and if disk 38 is momentarily held from continuous rotation by mechanism cooperating with the notches 39, arm 34 may move against either spring finger 37 or 36 depending on the direction of rotation and then when disk 38 is again released for rotation the spring finger 37 or 36 pressing against the pin 41 or 42 will quickly move the disk 38 to catch up the motion lost while the disk was held stationary. Inasmuch as it may be necessary at times to set the clock for accuracy, it is desirable that the drums may be rotated in a reverse as well as a forward direction and for this reason the spring finger and pins are provided on both sides of the arm 34 thus making it capable of transmitting the same type of motion to the drum control disk 38 in either direction. To set the clock it is only necessary to manually apply power to shaft 17 to rotate it in either direction, this being done by manually rotating the minute hand 13 in either direction. Rotation of the shaft 17 will then cause rotation of the drums in the same manner as though the clock were in operation, except that the rotation will be much more rapid, due to the rapid manual rotation of the minute hand 13.

In this description the forward face or front side of any parts is considered as being the side nearest the clock dial of the housing at 11 while the rearward side or back face is considered as being the opposite side or face nearer the other end of the housing toward the fixed plate 25. The disk 38 is therefore showing the forward face in Fig. 2. The forward face of the minute unit indicating drum 33 is provided with twenty equally spaced drum control stub pins 43, the distance between these drum pins 43 being somewhat less than the diameter of a roller 44 journaled on a roller shaft 45 carried by a roller arm 46 freely pivoted on a supporting shaft 47, supporting shaft 47 being carried by a leg 48 fastened at 50 to one of the pillars 51. The roller arm 46 is provided at its other end with a counterweight 52. Fixed on the roller arm 46 is a

cushioning spring 53 against which may press an abutting finger 54 of a spring arm 55 anchored at 56 in another of the clock pillars 57 and provided with a pawl elbow 58 which may enter into the notches 39 of the drum control disk 38. 5

While the pawl elbow 58 is in contact with the outer part of disk 38 its abutting finger 54 presses against cushioning spring 53 to hold the roller 44 between two of the stub pins 43 and prevent drum 33 from rotating. When pawl 58 momentarily enters one of the notches 39 the roller arm 46 is free to pivot about its supporting shaft 47 allowing the roller 44 to drop down and roll under one of the stub pins 43 to a position between that stub pin and the next pin 43 under the influence of the drum rotating mechanism about to be described. Meantime, while the pawl elbow 58 enters a notch 39 it momentarily prevents disk 38 from rotating, whereby arm 34 will press against the spring finger 36 in forward rotating direction. As soon as roller 44 enters into the next space between the pins 43, the pawl elbow 58 springs out of the notch and cannot reenter the notch because disk 38 will be immediately rotated by the spring 36 to bring that notch out 25 of radial alignment with the pawl elbow 58.

The mechanism causing the drum 33 to rotate whenever one of the notches 39 is radially aligned with pawl elbow 58 consists of drum actuating spring 60 held over a pin 61 extending into the forward face of drum 33. The ends 62 and 63 of the spring 60 are adapted at certain times to abut against short pins 64 and 65 fixed in the forward face of drum 33 on the other side of its bearing about the drum shaft 24. These pins 64 35 and 65 are spaced slightly apart. Between such pins at a slightly longer radius from the center projects a long pin 66 adapted to extend through a curved slot 67 and the hub 40 of disk 38. Extending from the rear face of the disk 38 is a short pin 69 which, as the disk 38 rotates, will press against the one or the other of the ends of spring 60, here being shown as pressing against the end 62. As the disk 38 rotates it presses against the spring end 62 storing up power in 45 the spring 60 which power in turn through pin 65 urges drum 33 to rotate in a direction identical with the rotation of disk 38. This rotation is prevented, however, by the roller 44 between stub pins 43 until the end of a minute, at which time 50 pawl elbow 58 will enter a notch 39 as it comes thereunder, releasing the roller 44 from the space between the two adjacent stub pins to thus allow the spring 60 through pin 65 to rotate the drum 33 to the next minute indicating position. 55

As this happens the roller 44 rolls under the stub pin 43 to the next space, the pawl elbow 58 comes out of the slot and the disk 38 is simultaneously rotated under the action of spring finger 36 sufficiently to prevent pawl elbow 58 from bouncing back into the slot and thus insuring that drum 33 rotates only one step during each actuation. The long pin 66 extending into curved slot 67 serves as a stop to prevent greater relative displacement than one step in either direction between the disk 38 and the drum 33 while the hook 59 on the spring end 63 holds spring 60 in proper position. By the mechanism thus far described the power of the main spring in case- 65 ment 15 is thus stored up in spring 60 and released once a minute to actuate the drum 33 intermittently. 70

As the drum 33 rotates in twenty intermittent steps per revolution and at three revolutions per hour it causes drum 32 to rotate one step for 75

every half revolution or ten steps of the minute unit indicating drum 33 so that during every hour the minute tens drum 32 is rotated six steps, for, as already explained, this drum 32 is provided with four series of numerals 28 and every time the drum 32 is rotated $\frac{1}{4}$ of a revolution or six steps it causes the hour drum 31 to rotate $\frac{1}{4}$ of a revolution or one step. The mechanism thus transmitting the step by step rotation of drum 33 to drum 32 and thus to drum 31 includes twenty-four disk headed pins 70 fixed on the forward face of each of drums 32 and 31 and equally spaced thereabout. Similar disk headed pins 71 and 72 are fixed on the rearward faces of the drums 33 and 32. There are but two pins 71 on the rear face of the drum 33, each spaced 180° apart, and there are four pins 72 on the back face of drum 32, each spaced 90° apart.

The mechanism for intermittently transmitting the motion of drum 33 to 32 and then drum 32 to 31 includes V-shaped arm 73 secured to the fixed arm shaft 24. One leg 74 of this V-arm 73 is offset as shown and carries a shaft 75 on which is journaled a frictionless pinion disk 76, the thickness and spacing of this disk 76 on shaft 75 being such that it may travel between the heads of pins 70 and pins 71 or 72. This disk 76 forms part of a frictionless pinion consisting of four shafts 77 extending to opposite sides thereof and carrying frictionless rollers 78 and 79, the roller 78 being carried so that the one most radially distant from the drum shaft 24 is in the circular path of the disk heads of pins 71 or 72 while the roller 79 on the other end is at the same time in the path of the heads of the pins 70. The diameter of the disk and spacing of the pins thereabout is such that if one roller leaves the path of the pins 70 and 71 or 72 the next roller enters the path thereof.

Inasmuch as there are but two pins 71, a half revolution of the drum 33 causes one step movement of the drum 32, and as there are four pins 72 every quarter revolution of drum 32 causes one step movement of drum 31. While the shaft 77 on disk 76 carries the rollers at opposite ends thereof, it is apparent that the disk headed pins 70, 71 or 72 might be similarly made with rollers instead of circular heads thereon so as to keep the friction at a minimum. These pins and the disk 76 thus provide a substantially frictionless pinion for transmitting motion of one drum to the next drum in the proper ratio.

In order to keep the drums from rotating except under the meshing action of this frictionless pinion, the other leg 80 of the arm 73 carries a drum position control roller arm 81 pivoted thereon, this arm 81 having a roller 82 at its other end freely rotatable about a shaft 83 extending from the arm 81, the diameter of this roller 82 being such that it will partly fit between any of the pins 70. Drums 33 and 32 each have a rearwardly extending flange 84 and 85, which flanges 84 and 85 are radially distant from the pins 70 a distance less than the diameter of the roller 82, thus keeping the roller 82 locked between the pins 70 and preventing any rotation of the drums.

In order to permit the desired rotation of the drums the drum flange 84 is provided with two cams comprising bevelled cuts 86 in flange 84, each cut being spaced 90° from the pin 71 thereon, this angle corresponding to the angle that the roller 82 is spaced about the drum shaft 24 from the center of the pinion disk 76. As the drum 33 rotates the head of a pin 71 will enter

the space between two rollers 78 at the same time that the roller 82 reaches the bevelled opening 86 in flange 84. The roller 82 is then free to roll into the opening 86 about the pin 70 and be locked in the space between that pin and the next pin as the disk 76 of the frictionless pinion is rotated one quarter of a revolution to thus rotate the drum 32 one step from one pin to the next, thus causing the drum 32 to be frictionlessly moved one step at every half revolution of the drum 33. The identical mechanism operates between drums 32 and 31 except that the flange 85 is provided with four bevelled cut-away openings 87 corresponding to the four pins 72 thus permitting the drum 31 to rotate one step for every $\frac{1}{4}$ revolution of the drum 32.

In operation the power of the main spring encased in 15 operates power shaft 17 and the hands 12 and 13 over the clock dial 11. Simultaneously through same shaft 17 and gear train 20 to 23 it rotates arm 34 to rotate disk 33 and through the notches 39 and spring 60 by means of pawl elbow 58 and roller 44 it intermittently rotates the minute unit drum 33. This drum 33 through the frictionless pinion on disk 76 and the roller 82 with the pins 70, 71 and 72 transmits this motion in proper timed sequence to the succeeding drums thus causing the numerals 28, 29 and 30 visible through a window 27 to correspond in their time indication with that of the hands 12 and 13. Due to the presence of spring fingers 36 and 37 on opposite sides of arm 34 and also the ends 62 and 63 of drum spring 60 on opposite sides of pins 64 and 65, the drums 31, 32 and 33 may be rotated in either direction in setting the clock by rotation of the minute-hand 13.

Other modifications and changes in the position and arrangements of the parts may be made by those skilled in the art without departing from the nature of the invention within the scope of what is hereinafter claimed.

The invention described herein may be manufactured and used by or for the Government of the United States of America for governmental purposes without the payment of any royalties thereon or therefor.

We claim:

1. A drum type clock comprising a plurality of time indicating actuatable drums, a clock mechanism, means connecting said clock mechanism to one of said drums and frictionless pinion means between each pair of said drums periodically transmitting the motion of each drum to each successive drum, said frictionless pinion motion transmitting means including a rotatable pinion between the adjacent faces of each pair of said drums, a great plurality of closely spaced pinion teeth on the forward face of each successive drum in constant mesh with the rotatable pinion adjacent said forward face and a lesser plurality of widely spaced pinion teeth on the rearward face of each drum in intermittent mesh with the rotatable pinion adjacent said rearward face, and means preventing rotation of said successive drums except when said rotatable pinion is in mesh with a pinion tooth of a preceding drum, said rotation preventing means comprising a flange on the rearward face of a preceding drum spaced from the pinion teeth on a succeeding drum, a roller of greater diameter than the space from the pinion teeth to the drum flange extending between said drum flange and the space between said pinion teeth, and cutaway cam surfaces in said drum flange corresponding to the space between two rollers 78 at the same time that the roller 82 reaches the bevelled opening 86 in flange 84. The roller 82 is then free to roll into the opening 86 about the pin 70 and be locked in the space between that pin and the next pin as the disk 76 of the frictionless pinion is rotated one quarter of a revolution to thus rotate the drum 32 one step from one pin to the next, thus causing the drum 32 to be frictionlessly moved one step at every half revolution of the drum 33. The identical mechanism operates between drums 32 and 31 except that the flange 85 is provided with four bevelled cut-away openings 87 corresponding to the four pins 72 thus permitting the drum 31 to rotate one step for every $\frac{1}{4}$ revolution of the drum 32.

in number and spacing to the pinion teeth on the rearward face of said drum, whereby said roller may enter said drum flange cutaway cam simultaneously with the intermittent meshing of one 5 rearward face pinion tooth with said rotatable pinion to free said succeeding drum for intermittent partial rotation.

2. In combination, a drum type clock comprising a plurality of intermittently actuatable 10 drums, a continuously operable power mechanism and means for intermittently storing power from the power mechanism and releasing it to the drums to successively actuate said drums in proper timed sequence, said intermittently power 15 storing and releasing means comprising a continuously operable disk, yieldable lost motion means connecting said disk to said continuously operable power mechanism, a spring connecting said disk to an adjacent face of the first of said drums, means locking said first drum against 20 rotation and means periodically unlocking said drum for intermittent partial rotation with said disk.

3. In combination, a drum type clock comprising a plurality of intermittently actuatable 25 drums, a continuously operable power mechanism and means for intermittently storing power from the power mechanism and releasing it to the drums to successively actuate said drums in proper timed sequence, said intermittent power 30 storing and releasing means comprising a continuously operable disk, yieldable lost motion means connecting said disk to said continuously operable power mechanism, a spring connecting said disk to an adjacent face of the first of said drums and means locking said first drum against 35 rotation.

rotation and means periodically unlocking said drum for intermittent partial rotation with said disk, said drum rotation locking means comprising a plurality of pins spaced about a face of said drum, a pivoted roller arm, a roller on said roller arm, and spring means pivoting said roller arm to hold said roller between any successive pair of said pins. 5

4. In combination, a drum type clock comprising a plurality of intermittently actuatable 10 drums, a continuously operable power mechanism and means for intermittently storing power from the power mechanism and releasing it to the drums to successively actuate said drums in proper timed sequence, said intermittent power 15 storing and releasing means comprising a continuously operable disk, yieldable lost motion means connecting said disk to said continuously operable power mechanism, a spring connecting said disk to an adjacent face of the first of said 20 drums and means locking said first drum against rotation and means periodically unlocking said drum for intermittent partial rotation with said disk, said drum rotation locking means comprising a plurality of pins spaced about a face of 25 said drum, a pivoted roller arm, a roller on said roller arm, and spring means pivoting said roller arm to hold said roller between any successive pair of said pins, said unlocking means including a ratchet means formed on said disk and a pawl 30 on said roller arm holding spring adapted to intermittently enter said ratchet means to release said roller from locking position.
